UNITED STATES PATENT OFFICE.

JOHN CARRINGTON BROOKE, OF CINCINNATI OHIO.

ASSEMBLY-CHAIR.

No. 889,578.

Specification of Letters Patent.

Patented June 2, 1908.

Application filed March 1, 1907. Serial No. 360,014.

To all whom it may concern:

Be it known that I, JOHN CARRINGTON BROOKE, a citizen of the United States of America, and a resident of Cincinnati, in the 5 county of Hamilton and State of Ohio, have invented certain new and useful Improvements in Assembly-Chairs, of which the following is a specification.

My invention relates to improvements on 10 those assembly chairs in which the seat is adapted to fold and the back is adapted to be tilted forward to facilitate the seating of an audience by providing additional room between the chairs for persons to pass in and 15 out and at the same time enabling the chairs to be placed nearer together and thus increase the capacity for seating in a room in which they are set up.

One object of my invention is to provide 20 an assembly chair with standards of sheet steel construction and which may be simple or elaborate according to the idea of the user while comprising but few parts.

Another object of my invention is to provide 25 a light inexpensive plain and durable two part sheet steel standard including the supporting base.

Another object of my invention is to provide 30 a vertically adjustable seat arm support.

Another object of my invention is to provide 35 an improved arm rest bracket.

Another object of my invention is to provide 40 an adjustable pivot support for the back.

Another object of my invention is to provide 45 an improved and durable link connection between the seat and the back.

Another object of my invention is to provide 50 an improved construction of side frame for a tilting back.

Another object of my invention is to provide 55 a vertically adjustable hat guard support.

Another object of my invention is to provide 60 a vertically adjustable foot rest or rail support.

With these and other objects in view to 65 perfect such chair my invention consists in the novel features of construction hereinafter described and claimed.

In order that my invention may be fully 70 understood I will proceed to describe it with reference to the accompanying drawing, in which

Figure 1 is a side elevation of my improved 75 assembly chair having a straight cushioned back and a cushioned seat arranged in normal

seating position. Fig. 2 is a vertical section thereof in folded condition taken on the line 2-2 of Fig. 3, a portion of the seat cushion being broken away. Fig. 3 is a front view 60 showing similar chairs of twin construction in folded condition. Fig. 4 is a side elevation showing a modified construction in which a plain standard, transversely curved plain back and a curved plain seat are employed, the adjustability of the seat arm support, and the hat guard support being shown in dotted lines. Fig. 5 is a back view 65 showing similar chairs of twin construction in folded condition. Fig. 6 is an inside view 70 of the plain standard, the adjustability of the foot rest socket being shown in dotted lines. Fig. 7 is a horizontal section of the arm rests between the twin chair backs taken on the line 7-7 of Figs. 5 and 6. Fig. 8 is a detail 75 side elevation of the lower part of the standard and its base plate showing the lower end as shaped for an inclined floor.

In carrying out my invention I provide a pair of plain skeleton thin metal standards 80 11 which are preferably made of sheet steel, wrought or malleable iron or cast steel, each having a substantial supporting base 12 provided with broad feet 13 secured by fastenings 14. These standards 11 are reinforced 85 by marginal flanges 15, and are further provided with foot rest rail sockets 16 and hat guard supports 17.

18 are seat arm supports or bracket arms formed on the standards 11 to which the seat 90 arms 19, carrying a seat 20 having a plain cushion 21 are connected by hinge joints 22 similar to that shown in Patent Number 707,547 issued to Finley S. Brooke, August 26, 1902.

At the inner side on the upper part of each 95 of the standards 11 are a pair of parallel horizontal curved flanges 23 spaced apart to provide a curved slide recess 24 in the center part of which is a bolt hole 25.

27 is a straight back or plain panel having 100 its side edges fitted into the longitudinal channels 28 of a pair of supporting side frames 29 each of I-shape in cross section and formed with lower and upper lateral projections 30 at right angles thereto, and having bolt holes 31 through which fastenings 32 are inserted for securing the back or panel to the side frames 29. The upper ends of the side frames 29 are curved rearwardly to provide 105 pockets 33 in which the upper curved edge 34 of the back panel 26 is fitted to pro-

100

105

110

vide a partial support to the latter. Each side frame 29 is also formed with an outwardly and forwardly projecting lug 35 having a bolt hole 36, receiving a pivot or hinge pin 37 mounted in a bolt hole 38 formed in the offset outer end 39 of an adjustable curved plate 40 fitted and slidable in the curved slide recess 24 between the horizontal curved flanges 23, having a horizontal bolt slot 41 with which the bolt hole 25 of the slide recess 24 registers.

42 is a clamping bolt extending through the bolt hole 25 and bolt slot 41 and having a binding nut 43 whereby the adjustable plate 40 is held to its adjustment for holding the back of the chair in desired position with relation to the standards 11.

44 is a forwardly and downwardly projecting offset hinge arm formed on the lower end 20 of the side frame and having a pivot-hole 45.

Formed upon the outer side of the seat arm 19 is an outwardly tapering horizontal tubular stud 46.

47 is a connecting link hinged at its forward end to a pivot-bolt 48 extending through the tubular stud 46 and secured by a nut 49. The rear end of the connecting link is hinged to the back arm 44 by a pivot pin 50 extending through pivot-hole 45. By this connection when either the back is thrown forward or the seat lifted these members will assume a vertical position within the bounds of the standards.

The upper ends 51 of the standards 11 are 35 so formed as to provide arm rests which may be provided with supplemental rests 52 suitably connected therewith by fastenings 53.

54 is a foot rest rail supported in the socket 16 and secured by fastenings 55 to the end 40 standards 11.

56 is a hat guard strip or rail mounted in its supports 17 and secured by fastenings 57 to the end standards 11.

In Figs. 4, 5, and 6 I show my preferred form of standard. 11^a is a thin plain rectangular vertical plate of malleable cast sheet steel and 12^a is a supporting base plate formed with a recessed marginal flange receiving the plate and riveted thereto and having 50 broad feet 13^a secured by fastenings 14^a. 18^a is a seat arm located in the same place as the standard and having an offset inner part adjustably secured to the standard 11^a by riveting it thereto. 26^a is a transversely 55 curved back to which the side frame 44^a is suitably secured by fastenings 44^b. This side frame 44^a carries the outwardly forwardly projecting lug 35^a which is connected to the curved plate 40. 51^a are offset arm 60 rests in the form of brackets located in the same plane as the standard and carrying the curved flanges 23 and are riveted to the standard 11^a. 16^a are the sockets for supporting the foot rest rail 54 adjustably 65 riveted to the standard 11^a, and 17^a are off-

set hat guard supports located in the same plane as the standards and adjustably riveted to the standard 11^a. The construction on one side of the chair is a duplicate of that on the other side thereof.

70 The standards may be made to fit an inclined floor by merely shearing off their lower ends as shown in Fig. 8.

When the seat arm supports are made adjustable the seats can be placed at any height 75 from the floor thus providing seats ranging from 12 to 18 inches high. Where the foot rest sockets are made adjustable it has advantage of locating the rest rail at the proper height. The hat guard supports when adjustable up and down can be arranged to suit different kinds of seats.

Having thus described my invention the following is what I claim as new therein and desire to secure by Letters Patent:

75 1. A chair comprising a standard consisting of a plate, an offset seat-arm support, a seat arm pivoted to the seat-arm support, an offset arm-rest bracket having horizontal flanges providing a slide recess, a back having a side frame formed with a forwardly projecting lug, and a hinge arm, an adjustable plate secured between the flanges of the arm-rest bracket and pivoted to the lug of the side frame, and a connecting link pivoted to the seat-arm support and to the hinge arm of the side frame.

90 2. An assembly chair comprising a standard having a pair of horizontal flanges at its upper end providing a slide recess and a bolt hole between the flanges, a back having a forwardly projecting lug provided with a pivot hole, an adjustable plate having a horizontal bolt slot, and a pivot hole at its rear end and fitting between the flanges, a bolt 95 extending through the bolt hole and bolt slot having a binding nut, and a pivot pin connecting the adjustable plate with the forwardly projecting lug.

100 3. An assembly chair comprising a standard having a pair of horizontal flanges at its upper end providing a slide recess and a bolt hole between the flanges, a back having a forwardly projecting lug provided with a pivot hole, an adjustable plate having a horizontal bolt slot, and a pivot hole at its rear end and fitting between and overlapping the flanges, a bolt extending through the bolt hole and bolt slot having a binding nut, and a pivot pin connecting the adjustable plate 115 with the forwardly projecting lug.

110 4. An assembly chair comprising a standard having a pair of horizontal curved flanges at its upper end providing a slide recess and a bolt hole between the flanges, a back having a forwardly projecting lug provided with a pivot hole, an adjustable curved plate having a horizontal bolt slot, and a pivot hole at its rear end and fitting between the flanges, a bolt 125 extending through the bolt hole and bolt slot having a binding nut, and a pivot pin connecting the adjustable plate 120 with the forwardly projecting lug.

bolt slot having a binding nut, and a pivot pin connecting the adjustable plate with the forwardly projecting lug.

5. An assembly chair comprising standards having seat-arm supports, seat-arms having outwardly projecting tubular studs, a back, side frames secured to the back and having lugs pivoted to the standards, and offset hinge arms, connecting links pivoted to the outer side of the hinge arms at their rear ends, and bolts pivoting the forward ends of the connecting links to the tubular studs.
10. An assembly chair comprising stand-

ards having seat-arm supports, seat-arms 15 having outwardly projecting tubular studs, a back, side frames secured to the back and having lugs pivoted adjustably to the standards, and offset hinge arms, connecting links pivoted to the outer side of the hinge arms 20 at their rear ends, and bolts pivoting the forward ends of the connecting links to the tubular studs.

JOHN CARRINGTON BROOKE.
